ABRASIVE WHEEL

Application filed September 29, 1926. Serial No. 138,495.

This invention relates to abrasive wheels and more particularly to an improved wheel composed of segments of bonded abrasive grain.

The modern abrasive wheel ordinarily is made by uniting abrasive grain, such as silicon carbide or crystalline fused alumina, with a suitable bond into a structure of desired shape. The utility of the wheel depends to a large extent upon the nature of the bond and the type and size of abrasive grain as well as the amount of each employed. The bond may be any one of various types, such as bakelite, rubber, silicate or shellac, but most commonly ceramic materials are employed which are vitrified or melted to a vitreous condition so as to grip the surface of the abrasive grain firmly and, to a limited extent, dissolve the surface material of the grain and unite therewith. The particular type of bond employed depends upon the type of grinding operation in which the wheel is to be used and whether a soft or hard grade wheel is desirable or required. Soft wheels generally contain a smaller amount of bond than the hard wheels and consequently the strength of the wheel is lower.

Wheels constructed for heavy duty operations usually contain large abrasive grains united by a small amount of bond, producing a wheel having a very porous and open structure and a relatively low strength. Heretofore, it has been impossible to construct a wheel, especially a wheel of large size or soft grade, which would effectively withstand the action of centrifugal force when rotated at an extremely high speed. It is not safe to rotate a solid wheel of a given material beyond a certain surface speed because there is danger of the wheel cracking or even flying in pieces. For example, it is universally acknowledged that for safe operation ceramic or silicate bonded abrasive wheels constructed in one piece should not be rotated at speeds exceeding about 6000 surface feet per minute.

Furthermore, in the manufacture of a large wheel composed of abrasive grain united by a ceramic bond there is great

danger of breakage of the wheel during the moulding and firing operation. The moulded article is friable and must be handled with great care to prevent injury thereto. When the moulded wheel is fired there is great danger of cracking since the size of the article prevents even distribution of the heat, and abnormal strains may be set up therein. Hence, breakage of the large sizes of wheels is frequent and expected.

Heretofore, some relatively large abrasive wheels have been manufactured by assembling a plurality of bonded abrasive segments upon a drum or so-called wheel center. In following such practice it has been necessary for the user, when in need of a new wheel, to return the wheel center to the manufacturer of the abrasive segments for mounting thereon. This involves considerable expense and often unduly delays the manufacturing operations of the user of the wheel.

It is an object of the present invention to provide a stronger and safer abrasive wheel composed of pieces or segments of bonded abrasive grain which are appropriately held together for shipment in the form of an integral wheel.

It is another object of the invention to provide an abrasive wheel constructed and arranged to minimize the effect of the action of centrifugal force so that the wheel may be rotated at a more rapid rate than has heretofore been possible without danger of breakage or reduction in the desired factor of safety.

The present invention contemplates the provision of an improved wheel composed of a plurality of segments of bonded abrasive grain suitably held together by an annular clamping device to form an integral wheel for shipment. The clamping device should be constructed and arranged for readily and conveniently securing upon a wheel center as well as for holding the segments securely in a desired position to present an abrasive surface. A facing of a suitable cementitious material may be interposed between the engaging surfaces of each seg-

ment and the clamping device to provide a firm and rigid engagement therebetween. The clamping device may include a pair of annular rings on opposite sides of the 5 segments held by an adjustable fastener extending between the segments.

The invention will be more clearly understood from the following description in conjunction with the accompanying drawings; 10 in which,

Fig. 1 is an elevational view of an abrasive wheel embodying the invention and operatively mounted upon a wheel center;

Fig. 2 is a partial sectional side elevational view of the same;

Fig. 3 is a perspective view of a segment illustrating the method of securing the clamping device thereto;

Fig. 4 is a partial sectional side elevation- 20 al view of a modified construction of wheel embodying the invention; and

Fig. 5 is a perspective view of a segment employed in the construction of such a wheel.

As illustrated in the drawings, a wheel embodying the invention may be formed of a plurality of bonded abrasive segments 10 so constructed that they may be held in spaced relation in the form of an abrasive 25 annulus or wheel by a suitable annular clamping device. As illustrated, the segments are provided with two concentric clamping shoulders 11 and 12 on its opposite exposed plane faces which slope outwardly 30 toward each other in such a manner as to form a wedge shaped clamping lug, and this lug is shaped and arranged to be engaged by correspondingly shaped beveled surfaces on a pair of clamping rings 13 located on 35 opposite sides of the wheel. In order that the rings may make a firm and rigid engagement with the segments, facings 14 and 15 of any suitable cementitious material, such as Babbitt metal, are interposed be- 40 tween the rings and the upper and lower clamping shoulders 11 and 12, these metal facings being ordinarily cast in place on the shoulders of the segments before they are assembled in position. The rings 13 45 of the clamping device are drawn towards the parallel plane surfaces of the segments by a fastener extending between the segments and adjustably secured to the rings. A suitable fastener may comprise a bolt 16 50 passing within grooves 17, as illustrated, in plane radial surfaces extending between two co-axial cylindrical surfaces on the segments, through openings 18 in the rings and adjustably secured thereto by nuts 19. The 55 spaces between the segments 10 may be filled by a suitable cementitious material 21, such as Babbitt metal or a mixture of sulfur and ground coke commonly known as lavasol. The clamping device should be constructed 60 and arranged for readily and conveniently 65

mounting upon a wheel center. In the construction illustrated each ring is provided with a lower wedge shaped portion 22 for clamping on a wheel center.

As illustrated in the drawing, the wheel 70 may be mounted upon a wheel center comprising a hub 25 provided with a radially extending web 26 terminating in a peripheral surface 27 having an upwardly projecting wedge-shaped flange 28 on one side 75 thereof and a removable clamping ring 28' on the other side against which the wheel of the invention may rest. The clamping flanges 28 and 28' on the wheel center are shaped to fit the wedge shaped clamping 80 rings 22, and they are adjustably secured together by bolts 29 passing through the inwardly projecting flange of the removable clamping ring 28' and the web 26 of the wheel center; whereby the abrasive ring 85 may be securely and rigidly clamped in place.

By constructing the wheel of the invention of a plurality of bonded abrasive segments, which are held together in the form 90 of an integral wheel by the molten metal or sulfur compound flowed into the crevices between the segments I have provided an abrasive annulus capable of being mounted as a unitary structure on a rotatable support. Also, by means of the clamping rings 13 adjustably engaging opposite sides of the abrasive annulus, I have provided a reinforcing or strengthening support for the annulus which makes it feasible to transport the wheel without danger of breakage. This wheel has a most rigid construction which will withstand safely rotation at speeds substantially greater than the maximum safe allowable speed of a solid wheel 100 of the same material, that is, of the same bond. Furthermore, the wheel of the invention provides all the advantages of a segmental wheel, and yet is preassembled in the form of an integral wheel for shipment so that the user may readily mount the same upon a wheel center.

In the modified construction illustrated in Figs. 4 and 5 the abrasive segments 30 are relatively large and are supported for 115 rotation at a point as near to the abrading surface 31 as possible. The segments 30 are held together in the form of an integral wheel and supported against the action of centrifugal force by a clamping device, such as rings 32 similar to those previously described, engaging oppositely beveled clamping shoulders 33 and 34 on the segments which form wedged shape portions adapted to be engaged by the clamping 120 rings. These rings 32 are held thereagainst by a fastener, such as a bolt 35, extending between the segments within a groove 36 therein and secured to the rings 32 by means of nuts 37. Preferably, a facing of a suit- 125 130

able cementitious material 39, such as Babbitt metal, is interposed between the engaging surfaces of the segments and the clamping device. The bottom portion of the 5 clamping device is arranged with a wedge-shaped portion 40 for securing upon a suitable wheel center 41 in the same manner as described with reference to the construction shown in Figs. 1 and 2.

10 The segments 30 are provided with beveled clamping shoulders 42 and 43 between the abrading surface 31 and the rings 32 for engagement by annular rings 44 and 45 respectively which are held thereagainst 15 by bolts 46 and 47 passing through grooves 48 and 49 respectively in the inner faces of the segments and secured to the rings 44 and 45 by nuts 50 and 51. Facings 52 and 53 of a suitable cementitious material, 20 such as Babbitt metal, may be interposed between the annular shoulders 42 and 43 respectively and the rings 44 and 45. When the segments 30 wear down to the 25 rings 44 and 45 the latter are removed. In this manner a wheel is provided having a long useful life as well as one which is supported against the action of centrifugal force at a point as near as possible to the abrading or outer surface.

30 Having thus described my invention, what I claim as new and desire to secure by Letters Patent is:

1. A segmental grinding wheel comprising a plurality of abrasive segments arranged in the form of an annulus, the annulus having on each of its opposite sides two opposed beveled clamping shoulders sloping in opposite directions and forming a wedge shaped clamping lug, a clamping 35 plate on each side of the annulus provided with beveled faces corresponding with the clamping shoulders on the annulus, and means to draw the plates together, said parts being so arranged that the annulus 40 is supported wholly by its beveled clamping shoulders.

2. A grinding wheel comprising an abrasive annulus having clamping shoulders on opposite sides thereof, clamping rings on 50 opposite sides of the annulus in engagement with said shoulders and serving as an independent support for the abrasive body, means removably securing the rings in position, and a rotatable wheel center having 55 clamping members removably carrying the rings.

3. A segmental grinding wheel comprising a plurality of abrasive segments arranged in the form of an annulus, each segment having on each of its exposed sides two beveled faces which provide a wedge shaped clamping lug, a pair of supporting plates on opposite sides of the annulus having beveled faces engaging the beveled faces 60 on the lugs, means for adjustably clamping

the plates against the sides of the wheel and removable means for rotatably supporting said annulus and plates.

4. A grinding wheel comprising an abrasive annulus having on each side thereof a beveled clamping face and a supporting face, 70 clamping rings on each side of the annulus engaging the same, means for adjustably clamping the rings securely against the annulus, a wheel center, and means for removably mounting the rings thereon. 75

5. A segmental grinding wheel comprising a plurality of abrasive segments arranged in the form of an annulus, the annulus having on opposite sides thereof two 80 opposed clamping shoulders, shoes thereon having beveled faces sloping in opposite directions to form a wedge shaped clamping lug, two opposed clamping rings having beveled faces engaging the shoes on opposite sides of the annulus, and means to draw 85 said rings towards each other to clamp the abrasive segments rigidly in position.

6. A segmental grinding wheel comprising a plurality of abrasive segments arranged in the form of an annulus, each segment having two clamping shoulders on opposite sides thereof, a beveled facing integral with each shoulder which is so arranged as to form a wedge shaped clamping lug, 90 clamping rings on opposite sides of the annulus which have faces engaging the beveled faces of said clamping lugs, means to draw said clamping rings towards each other to secure said segments rigidly in position, and means for removably mounting the rings on a rotatable support. 95

7. A segmental wheel comprising a series of abrasive segments arranged in the form of an annulus, a cementitious filler between the segments uniting them into an integral structure and reinforcing annular members 100 removably clamping against the sides of the segments and forming an abrasive body transportable independently of a wheel support, said structure having opposed beveled shoulders engageable by clamping members for rotatably mounting the same on a support. 105

8. A segmental grinding wheel comprising a plurality of abrasive segments arranged in the form of an annulus, said annulus having beveled clamping shoulders on its opposite side faces and a supporting face on its inner periphery, a facing shoe on each 110 beveled clamping shoulder and a cementitious filler between the segments which unites them into an integral body, and reinforcing members clamping against said faces and forming a carrier for the annulus, which is independent of any rotatable support, said members having provisions for mounting the annulus on a wheel center. 125

9. A segmental grinding wheel comprising a plurality of abrasive segments ar- 130

ranged in the form of an annulus, said annulus having clamping shoulders on opposite sides thereof, a facing shoe on each clamping shoulder, a filler of cementitious material between the segments which unites them into an integral body and removable clamping members adjustably engaging the shoulders and reinforcing the sides of the wheel, said annulus and clamping members forming a rigid wheel structure which is independent of any rotatable support.

10. A segmental grinding wheel comprising a plurality of abrasive segments arranged in the form of an annulus which has 15 a peripheral grinding face and substantially parallel side faces, the annulus having oppositely beveled clamping shoulders on each side thereof forming wedge shaped supporting lugs, and a filler of cementitious material between the segments which unites them into an integral body.

11. A grinding wheel comprising an abrasive body having a series of concentric shoulders on each side thereof, a series of 25 concentric, removable, clamping rings engaging the shoulders on each side of the wheel, means to secure the rings against the side faces of the wheel to reinforce the same during rotation thereof, and a wheel center 30 having clamping members removable independently of the rings which engage a set of said rings and support the abrasive body.

12. A segmental grinding wheel comprising a plurality of abrasive segments arranged in the form of an annulus, said annulus having a series of concentric beveled 35 clamping shoulders on each side face thereof, a series of beveled clamping rings engaging the clamping shoulders on each side 40 of the annulus, means to secure the opposed beveled rings together and hold the segments against breakage and means for removably and wedgingly mounting the inner set of clamping rings on a rotatable 45 wheel center.

13. A grinding wheel comprising a series of abrasive segments arranged in the form of an annulus which has clamping shoulders on opposite sides thereof, clamping 50 rings removably and adjustably secured against said shoulders and serving to support and reinforce the annulus, said rings having beveled clamping faces for mounting on a wheel center, and adjustable opposed clamping members wedgingly engaging the beveled faces on the rings and supporting the same.

Signed at Worcester, Massachusetts, this 24th day of September, 1926.

THURE LARSSON.
